R. PAUL.
STYLUS HOLDER.
APPLICATION FILED MAY 31, 1918.

Patented Dec. 3, 1918.

UNITED STATES PATENT OFFICE.

RAYMOND PAUL, OF CHICAGO, ILLINOIS, ASSIGNOR TO GAINER & KOEHLER, OF CHICAGO, ILLINOIS, A COPARTNERSHIP COMPOSED OF EDWARD J. GAINER AND JOHN E. KOEHLER.

STYLUS-HOLDER.

1,286,759.

Specification of Letters Patent.

Patented Dec. 3, 1918.

Application filed May 31, 1918. Serial No. 237,442.

To all whom it may concern:

Be it known that I, RAYMOND PAUL, a citizen of the United States, residing at Chicago, in the county of Cook and State of Illinois, have invented certain new and useful Improvements in Stylus-Holders, of which the following is a specification.

This invention relates to talking machines and has for its object the provision of means on the sound box or reproducer whereby the stylus may be readily inserted and removed without the necessity of manipulating screws or other fastening means.

A further object of my invention is the provision of means whereby my improved stylus holder is readily adaptable to sound boxes of usual construction without interfering with or modifying the structure thereof.

Further objects and advantages of my invention reside in the various combinations hereinafter claimed as will be better understood by reference to the following specification when read in connection with the accompanying drawing illustrating the preferred embodiments thereof, in which—

Figure 1 is a side elevation of a sound box embodying my invention;

Fig. 2 is an enlarged detail in section of the invention;

Fig. 3 is a section on the line 3—3 of Fig. 2;

Fig. 4 is an enlarged detail in section of a slightly different form of my invention, and

Fig. 5 is a section on the line 5—5 of Fig. 4.

Referring to the drawing, 5 indicates a sound box of any suitable or usual form of construction carrying a pivoted stylus lever 6 which is connected at one end to the diaphragm 7 and at the other end is provided with an enlarged head 8 having a socket to receive the stylus 9. The head 8 is grooved to receive a spring 10 which is fastened at one end therein and which at its other end bears against a ball 11 in a recess 12 connecting with the groove and socket in the head. A cover plate 13 is fastened by screws or other suitable means to the head 8 and conceals the spring 10.

The ball 11 is normally held by the spring 10 so that it protrudes into the socket in the head 8. When the stylus 9 is inserted in the socket it engages the ball 11 and forces the

spring 10 outwardly. The ball permits easy insertion and withdrawal of the stylus and the spring clamps the stylus between the ball and the opposite side of the socket, holding it firmly in position to coöperate properly with the record during the reproduction.

In Figs. 4 and 5, I have illustrated a slightly different form of my invention intended for use in adapting my invention to common forms of sound boxes without changing or modifying their construction.

In this form of my invention the usual clamping screw is removed from the head 14 and the stylus lever and the supplemental head 15 is secured thereto by means of a screw 16 which engages the opening provided for the usual clamping screw.

The supplemental head 15, which forms an extension of the head 14, is provided with a socket which alines with the socket in the head 14. The supplemental head 15 is grooved to receive a spring 17, one end of which is secured to the supplemental head while the other bears against a ball 18 disposed in an opening communicating with the socket and groove. A plate 19 secured to the supplemental head by screws or other fastening means covers the spring 17. The mode of operation of this form of my invention is identical with that of the form

previously described. The stylus is held in the socket by the operation of the spring 17 which firmly clamps the stylus between the ball 18 and the opposite side of the socket.

The stylus may be easily inserted and withdrawn, the operation being facilitated by the ball 18 which revolves as the stylus is moved in or out of socket.

From the foregoing it will be readily understood that I have perfected a novel means for holding a stylus in the talking machine which dispenses entirely with the usual clamping screw. This screw is small and difficult to manipulate; may become loose or misplaced and frequently does not grip the stylus with sufficient rigidity to insure proper reproduction if carelessly handled. My improved stylus holder insures gripping of the stylus with the same degree of pressure which is sufficient to hold it in proper relation to the stylus lever during the reproduction.

Various changes may be made in the form, arrangement and construction of the parts without departing from the spirit and scope.

2
of the invention or sacrificing any of its material advantages, the form hereinbefore described being merely the preferred embodiment thereof.

5 I claim:

1. A stylus holder for talking machines comprising a head having a socket to receive the stylus and a recess communicating with said socket, a ball supported in said recess 10 to engage the stylus, and a flat spring disposed opposite the stylus and engaging the ball to hold said ball in engagement with the stylus.

2. A stylus holder for talking machines comprising a head having a socket to receive the stylus, an extension on said head having a socket alining with the socket in the head and also having a recess, a ball in said recess arranged to engage the stylus, a spring engaging the ball to hold it in engagement 15 with the stylus, and means for securing the extension and spring to said head.

RAYMOND PAUL.
